CLAIM

The ornamental design for a vacuum cleaner, as shown and described.

DESCRIPTION

FIG. 1 is a front, perspective view of a vacuum cleaner, showing my new design;

FIG. 2 is a rear, perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is an enlarged view of the area labeled 9 in FIG. 1. The broken lines show portions of the vacuum cleaner that form no part of the claimed design.

The dashed lines in the figures illustrate portions of the vacuum cleaner that form no part of the claimed design.

The dot-dash broken lines of the vacuum cleaner in FIG. 1 illustrate a boundary and cut line of the enlarged view in FIG. 9 and form no part of the claimed design.
